UNITED STATES PATENT OFFICE.

JAMES W. SILVER, OF OGDEN, UTAH.

ENDLESS SCREEN CONVEYER.

Application filed May 2, 1927. Serial No. 188,270.

This invention relates to improvements in endless screen conveyers, of the slatted belt type, which have their conveying surface formed of spaced bars extending transversely between and carried by side sprocket chains or their equivalent.

Although the improvements primarily have been designed as further desirable equipment for the sugar beet screening conveyor covered in the J. A. Lynch United States patent, for beet dumps, No. 1,432,195 of October 17, 1922, and while the improvements shall hereinafter be disclosed more particularly in such relations, still it is to be understood that they are not to be limited in this respect, but may be employed in any other equivalent or analogous uses.

A vertically agitating motion is preferably imparted to the upper or conveying portion, of such conveyers, to cause a shaking or abrupt raising and lowering thereof for more effective screening purposes, which motion may be attained by impacting means located underneath said upper portion. The inner end of the conveyer is associated with the open top of a tare receptacle or dirt hopper, and the lower or return portion of the conveyer is positioned, along its forward zone, immediately over an apron base or skirt board therefor, discharging into said receptacle for important reasons well understood in the weighing and screening of dirty loads of beets, the dirt and leafy refuse being fed along said base board by the scraping action of the spaced bars of the conveyer traveling thereon.

These types of screening conveyers in the main serve their aims very well indeed, but obviously there is a materially destructive wear on their spaced cross bars, as they ride upon said base board, which wear is greatly augmented by an abrading action of the dirt itself. Also, the leafy refuse of the beets, although normally more or less free to drop between said spaced bars during the latter's conveying travel, when fed along said base board under the scraping force of said bars, on the return travel of the latter, some of said leafy refuse not infrequently becomes entangled across the bars, being thus carried around the upper conveying zone, so that to some extent such leafy refuse obstructs the spaces between the bars, and accordingly interferes with maximum screening of the dirt from the beets, which beets are discharged over the outer end of the conveyer. Even

more important still, however, in actual operations under some soil conditions, say in wet weather and especially with muddy and the more tenaciously clinging clay soils, considerable difficulty and trouble have been experienced in attempting to maintain said base board clean or clear of sticky soil or hard deposits formed thereby and accumulating on said base board. It will be apparent that all of the foregoing features are seriously disadvantageous, for the reasons stated and various others unnecessary to enumerate.

Accordingly, an important object of the present improvements has been to devise simple, economical and effective means for overcoming the aforesaid disadvantageous features, but this and other objects and advantages, however, will more clearly appear, it is believed, as incidental to the following disclosure, and with these outlining remarks, therefore, reference will now be had to the accompanying drawings, illustrating a practical embodiment of the improvements, in which drawings

Figure 1 is a vertical longitudinal sectional view of a bar screen conveyer of the type aforesaid, with my improved equipment applied, and as associated with the dirt receiving hopper or tare receptacle fragmentarily shown; Figure 2 is an analogous view but broken away in parts and drawn on a substantially larger scale; Figure 3 is a fragmentary plan view looking down on Figure 2 at a position where one of a series of scraping units is attached, in accordance with the main feature of the improvements; Figure 4 is a transverse sectional view through one of the elements of such scraping units, where such scraping units are of sectional construction which is preferred, and being shown as of triangular shape; and Figure 5 is a central vertical longitudinal sectional view of Figure 4.

Referring briefly to the bar belt screen conveyer itself, which in beet dumps or the like is either directly or indirectly associated with a main inclined conveyer to receive the discharge therefrom, the numeral 10 indicates the series of spaced cross-bars that may be supported at their ends by side sprocket chains but which, as actually shown, embody suitably bent ends 11 to provide link-like hooks or looped connections between adjacent bar ends. This bar belt conveyer reeves over end supporting rollers which may consist of head sprocket or toothed wheels 12,

keyed to a drive shaft 13 therefor, and a pair of tail idlers 14 which may be toothed or otherwise. Side guards for the conveyer are indicated at 15, but only the one on the far side actually appearing on the drawings, and 16 are suitably mounted idler rollers, which may be employed for supporting the upper portion of the bar belt intermediately of said head and tail rollers, while the numeral 17 indicates the aforementioned apron base or skirt board, disposed immediately under the forward return portion of said bar belt, and discharging into the dirt hopper or tare receptacle 18. A drive shaft, for a rotary agitator, is shown at 19, which shaft is geared up with the drive shaft 13, of the bar belt, as indicated at 20—21—22, and 23 is a belt or sprocket chain for driving said agitator shaft 19 from any suitable source, as 24 from the head drive of a preceding conveyer, the aforesaid gearing being simply illustrated in dotted outline. The foregoing features are broadly old, as disclosed in my own prior application or in the Lynch patent 25 aforesaid.

However, in addition to the scraping units before mentioned, which perhaps are the more important feature of the present improvements, there is also embodied in the 30 present case improved means for more effectively imparting a vertically agitating motion to the entire conveying portion of the bar belt, with a wave-like shaking motion as it were, and which feature will now be described in advance of the detailed description of the scraping units.

The agitator shaft 19, located towards the inner end of the conveyer to be disposed over the dirt hopper 18, is supplemented by 40 a plurality of such shafts carrying rotary agitators, two being actually shown between said first agitator and the outer end of the conveyer. These additional shafts are indicated at 24 and 25, and may mount sprocket wheels 26 and 27, or their equivalent, shown in dotted outline at Fig. 1, which are driven by the element 22, but it is obvious that other means may be employed for driving the several shafts.

As these rotary agitators, or beater-like shakers, are of the same construction, there will only be described the central one which is shown on an enlarged scale at Figure 2.

The cross-shaft 24 mounts a spaced pair 55 of side supports, shown as spider elements embodying three equidistantly spaced radial arms 28, for each said spider, and between each of the complementary arms thereof there is disposed a cross-member 29, which may be an elongated roller if desired, adapted in its revolutions to engage and recede from the underneath side of the upper or conveying portion of the bar belt, causing at predetermined intervals the raising and 60 lowering of the latter, at the position of the

particular agitator. These rotary agitators are so arranged, in geared relation, that the cross-members 29 of the alternate agitators are relatively in and out of approximate operative engagement with said upper conveyer portion, being always out of engagement with the lower portion thereof. Accordingly, with a plurality of these rotary agitators or their equivalent, disposed along the underneath side of said upper conveyer portion, the latter is vertically agitated or jiggled, approximately along its whole length, with an undulatory or wave-like shaking motion, which insures the more effective screening of the dirt and other refuse from the beets conveyed along said upper conveyer portion.

With reference to the aforementioned scraping units, these are carried as a suitably spaced series by said bar belt, being generally designated as complete units by the numeral 30 in Figures 1 to 3, and the number of these units to be employed will largely be dependent upon the actual length of the conveyer and the particular operating conditions. In some instances the scraping units might be spaced approximately three feet apart, while in other instances the distance could be greater. In broad principle each of these scraping units could be a single element, or its equivalent, and, whether integral or sectional in structure, each of said units could have a greater number of sides than three. As a matter of practice and present preference, however, each unit is shown as being of sectional form, see Figure 3, with each section thereof being of triangular shape and mounted for either conjoint or independent pivotal motion, which independent pivotal motion has its own particular advantages as will later appear.

Referring now more particularly to Figures 3 to 5, each of the triangular sections or blocks should provide means for the facile mounting and demounting thereof, as may be desired for replacements or other purposes. A practical and preferred means for doing this is to provide one base side with a substantially deep slot 31, extending centrally and longitudinally for the full length of that side, and which side is also provided with paired slots at each side of said central slot, which paired end slots open as recesses to the respective other two sides of the section, adjacently of the ends thereof, as respectively indicated at 32—33 and 34—35. The central longitudinal slot 31 is adapted to freely encompass a desired one of the cross-bars 10 of the conveyer, and the section is pivotally held thereon by an elongated retaining bar 36 that extends along within the base of said slot, being securely held in place as by means of bolts or rivet rods 37.

As shown at Figure 3, the triangular block sections are disposed in endwise relation on

their conveyer bar 10, the several sections embodying a complete one of the said scraping units, and may be held against undue lengthwise displacement thereon by any suitable means, such as segmental collars or the like indicated at 38.

Also, at Figure 3, different respective base sides of the triangular block sections are shown as disposed uppermost to illustrate that the sections may hang at any positions during their travel, except during their travel along said base board 17 when they become normally disposed with one of their base sides, although it is immaterial which one, adapted for riding along upon said base board, in cleaning or scraping relation therewith.

In operations, it is understood that the material, such as sugar beets associated with dirt and other refuse from the field, is gradually fed upon the inner end upper portion of the conveyer, being carried forward thereby for discharging the cleaned product over the outer end thereof, whereas the refuse therefrom drops through between the upper spaced bars, and this screening operation is more effectively attained, as heretofore set forth, by the particular arrangement and functioning of the aforesaid rotary agitators.

The refuse that drops through between the upper bars, at the inner end of the conveyer, will also drop through the lower bars, at that end, and directly into the tare hopper 18. Forwardly of said hopper, however, the

refuse matter will drop down upon the lower bars and partly, therebetween, upon the base board 17, along which said base bars are then traveling, and, heretofore, was dragged therealong, for discharging into said hopper, solely by and between said lower spaced bars. Under these prior arrangements, not only has this feed or dragging of the refuse material into the dirt hopper been at times more or less unsatisfactory, especially under certain sticky soil and clayey conditions as before set forth, but also as the spaced bars of the conveyer ride directly upon said base board, they are subjected to considerable abrading wear.

By the present improvements, however, it will be observed that the lower spaced bars, when traveling along over the base board 17, are not in direct contact with the latter, but are in fact supported in substantially spaced relation therefrom by the scraping units, which feature not only permits the refuse material to more completely drop down upon the said base board, between said spaced bars, but which also relieves said bars from all abrading wear thereon, and the dirt and other refuse material being pushed or scraped along the base board by the action primarily of the scraping units themselves.

Regardless of the hanging position thereof, when the scraping units enter the zone of

the base board 17, as best seen by the scraping units at the extreme right end of Figures 1 and 2, each section thereof is partially rotated on its pivotal axis to bring respective base sides of the unit, it is immaterial which ones, into flatwise position on the base board, and this partial rotation of the individual sections has a tendency to and will shear or tear or twist off leafy refuse matter, common to sugar beet loads from the fields, which may have become entangled upon or entwined about scraping units. Also, in traveling along the base board, if any of the sections encounter a heavy lump of mud or like obstruction, it will have a gouging-like action thereon, which would tend to forwardly tilt the scraping unit section momentarily, and this tendency causing a further shearing action, on any entwined leaves, relatively to the next adjacent triangular section.

From all of the foregoing, it is believed that the objects, advantages and functioning of the improvements will be clearly apparent, but although I have thus set forth the same fully, in accordance with my present preferences, it will nevertheless be understood that I do not wish to unnecessarily confine myself to all of the details exactly as disclosed, excepting as they may come within the terms or tenor of the ensuing claims, or equivalent elements and combinations thereof, or as fairly interpreted in the light of the specification if necessary.

What I do claim, as new and patentable, is:

1. The combination of an endless screen conveyer, having spaced cross-bars, a base board over which said conveyer operates, an elongated block pivotally mounted on a complementary one of said cross-bars, in operative relation to said base board, said block having a substantially deep central longitudinal slot, opening to a base face thereof for the entire length of the latter, in which slot said complementary cross-bar is longitudinally disposed, a bearing and retaining bar, for said complementary cross-bar, extending along within said slot exteriorly of said complementary cross-bar, and securing means holding said bearing and retaining bar in position.

2. The combination of an endless screen conveyer, having spaced cross-bars for its conveying means, a base board over which said conveyer operates, and a series of elongated flat sided scraping units carried by and extending transversely of said conveyer in operative contacting relation to said base board, each of the said scraping units being mounted for rotation, axially of its length, on and around a complementary cross-bar of said conveyer.

3. The combination of an endless screen conveyer, having spaced cross-bars for its conveying means, a base board over which

- said conveyer operates, and a series of elongated flat-sided triangularly-shaped scraping units carried by and extending transversely of said conveyer in operative contacting relation to said base board, each of the said scraping units being mounted for rotation, axially of its length, on and around a complementary cross-bar of said conveyer.
4. The combination of an endless screen conveyer, having spaced cross-bars for its conveying means, a base board over which said conveyer operates, and a series of sectionally elongated scraping units carried by and extending transversely of said conveyer in operative relation to said base board, each section of said respective units being mounted for rotation, axially of its length, on and
5. The combination of an endless screen conveyer, having spaced cross-bars for its conveying means, a base board over which said conveyer operates, and a series of sectionally divided elongated scraping units carried by and extending transversely of said conveyer in operative relation to said base board, each section of said scraping units being of triangular shape in cross-section and being mounted for individual rotation, axially of its length, on and around a complementary cross-bar of said conveyer.

around a complementary cross-bar of said conveyer.

5. The combination of an endless screen conveyer, having spaced cross-bars for its conveying means, a base board over which said conveyer operates, and a series of sectionally divided elongated scraping units carried by and extending transversely of said conveyer in operative relation to said base board, each section of said scraping units being of triangular shape in cross-section and being mounted for individual rotation, axially of its length, on and around a complementary cross-bar of said conveyer.

In testimony whereof, I affix my signature.

JAMES W. SILVER.
